(57) **CLAIM**

We claim the ornamental design for the server control panel, as shown and described.

DESCRIPTION

FIG. 1 is a front perspective view of the server control panel comprising the present invention installed on a server information handling system;

FIG. 2 is a front perspective view thereof separate from the server information handling system;

FIG. 3 is a front view thereof;

FIG. 4 is a left or right side view thereof;

FIG. 5 is a rear view thereof;

FIG. 6 is a top view thereof; and,

FIG. 7 is a bottom view thereof.

Broken lines shown in the drawings illustrate portions of the rack server control panel, and form no part of the claimed design.
